UNITED STATES PATENT OFFICE.

CAMPBELL WOOD, OF DETROIT, MICHIGAN.

DISPLAY DEVICE.

Application filed November 24, 1924. Serial No. 751,789.

My improved device relates to that type of display rack wherein three adjustable arms are adapted to support articles to be displayed upon a board or like device.

5 It is the primary object of my invention to provide means for maintaining the devices or articles being displayed in a uniform position irrespective of whether the rack is filled with such devices or articles 10 or only partially filled.

It is a further object to so construct the arms utilized in my improved device that advertising matter or the like contained on the front of the articles being displayed may 15 be easily seen when it extends to the outer edges of the article.

It is a still further object to provide a device of cheap and economical construction, as well as of neat and ornamental appearance 20 so as to be pleasing to the eye.

With the above, and other objects, in view, my invention consists in the arrangement, combination and construction of the various parts of my improved device, as described 25 in the specification, claimed in my claim and shown in the accompanying drawings, in which:

Fig. 1 is an elevation showing my improved device.

30 Fig. 2 is a sectional view taken on line 2-2 of Fig. 1.

I have shown a rack consisting of two side arms 5 and 6 having slots 7 and 8 respectively provided therein. A bottom arm 35 9 having a slot 10 therein is also provided. The three slots 7, 8 and 10 are provided with a common guide member consisting of a rivet 11, so that when the arms are moved inwardly or outwardly, the rivet 11 may 40 act both as a guide member and a stop for limiting the movement of the arms.

I also provide a base plate 12 and a top plate 13, which may be joined together at their four corners by welding or otherwise, 45 in order to make the device of a unitary construction.

The device may then be secured by tacks or other similar means through the openings 14 in the four corners thereof to a display board 15.

The plates 12 and 13 are of thin relatively flexible metal which bears against the arms 5, 6 and 9 so as to hold them in any desired adjusted position and at the same

time permit the movement of the arms either 55 inwardly or outwardly by the exertion of a slight pressure thereon.

The ends of the arms 5, 6 and 9 are bent forwardly to form end portions 16 and then are reversely bent to form front portions 60 17. The front portions 17 are provided with cut out openings 18 and are of curved formation so as to cause them to project over the advertising material or other article being displayed, shown as 19, to a greater extent in the center thereof than at the edges thereof. The cut out portions 18 make possible the reading of any matter on the advertising or other matter 19, which may extend to the edges thereof and the tapering 65 of the portions 17 of the arm from the edges thereof, provides a relatively far reaching portion of the arm for holding the advertising or other matter in place and at the same time utilizes a relatively small amount 70 of the face of the advertising or other matter. 75

Positioned on the plate 13 and secured thereto, as at 29, by welding or otherwise, is a strip of relatively thin and flexible material 20 bent so as to normally extend to a position substantially flush with, or a little beyond, the outer face of the portion 17 of the arms 5 and 6. When the rack is filled with advertising matter, or other articles 80 being displayed, the flexible member 20 will be depressed toward the arm 9, whereas when the rack is not filled, the flexible member 20 will press outwardly against the advertising or other matter 19 so as to maintain the same constantly pressed against the portion 17 of the arms and cause the rack to 85 90 appear filled.

It is obvious that the spring or flexible member 20 may be utilized in any one of 95 a number of different manners and that various other changes may be made in the arrangement, combination and construction of the various parts of my improved device without departing from the spirit of my invention, and it is my intention to cover by my claim such changes as may be reasonably included within the scope thereof. 100

What I claim is:

In a rack for holding advertising matter, 105 the combination of a plurality of intersecting arms each having a slot adjacent one end thereof and each having the other end there-

of apertured and return bent to form hooks for supporting advertising matter, a base plate having apertured corners positioned beneath the intersection of said arms, a rivet in said base plate extending through the slots in said arms, a top plate having apertured corners aligned with the aper-

tured corners of said base plate positioned over the intersection of said arms and engaging said rivet, and a spring finger on 10 said top plate extending outwardly therefrom, for holding advertising matter in an upright position in said hooks.

CAMPBELL WOOD.
